**REVERSIBLE DRIVE RATCHET HAND TOOL
WITH SPHERICAL HANDLE**

Carlton L. Whiteford, Westport, Conn., assignor to
Creative Tools, Inc., Bennington, Vt.

Filed Feb. 7, 1973, Ser. No. 330,174

Term of patent 14 years

Int. Cl. D8—04

U.S. Cl. D8—82

FIG. 2

FIG. 3

FIG. 1

FIG. 1 is a side elevational view of a reversible drive ratchet hand tool with spherical handle showing my new design, all side elevational views being substantially the same;

FIG. 2 is a top view thereof; and

FIG. 3 is a bottom view thereof.

I claim:

The ornamental design for a reversible drive ratchet hand tool with spherical handle, as shown and described.
